UNITED STATES PATENT OFFICE.

KARL PETTER NILSSON, OF STOCKHOLM, SWEDEN, ASSIGNOR, BY MESNE ASSIGNMENTS, TO THE DE LAVAL SEPARATOR COMPANY, OF NEW YORK, N. Y., A CORPORATION OF NEW JERSEY.

CENTRIFUGE RECEPTACLE PROVIDED WITH DROP RIDGES.

Application filed June 27, 1923, Serial No. 648,114, and in Sweden August 16, 1922.

As is well known, a rotating centrifuge bowl to a certain extent acts as a fan, thus causing a circulation of air through the centrifuge receptacles adapted to collect the liquids issuing from the bowl of the centrifuge. In order to alter, more or less, the directions and the intensities of these air currents, and thus to prevent vapour and foam from being sucked from the collecting vessels for the separated liquids into the compartment surrounding the bowl, there have been provided radial or oblique (spiral-shaped) ridges in the vessels. For reasons that need not be mentioned here, the air is generally sucked in through the liquid outlet of the upper collecting vessel, and after it has passed through the collecting vessels, it is blown out, partly through the liquid outlet of the lower collecting vessel, and partly through openings in the top portion of the compartment surrounding the bowl. However, in addition to this air current which communicates, on the pressure side as well as on the suction side, with the space surrounding the separator, there also occur closed or whirling air currents within the vessels. Hitherto, the occurrence of such whirling currents has not been taken into consideration in any higher degree, as they do not involve any inconveniences in milk separators.

However, if it is desired to completely relieve a light liquid such as benzine escaping through an upper liquid outlet of a heavier liquid, such as water, which escapes through a lower outlet, it will be found that such closed or whirling air currents cause a certain though only inconsiderable remixing of the two liquids.

The present invention has for its object to hamper such air currents, or to entirely prevent their origination, and also to separate the fine liquid particles entrained by said air currents. The invention is principally distinguished by the fact that suitable members are arranged within the area where such air currents are apt to occur, in such a manner as to alter the direction of the air currents produced, while at the same time catching drops of liquid entrained by the air currents, so that these drops may gradually fall down and enter the proper vessel. Preferably, said members are con-

stituted by rings or ridges which are preferably disposed in concentric relation to the bowl, or substantially so, within the area where the prevention of such air currents is desired. Such an embodiment of the invention is disclosed in Fig. 1 of the accompanying drawings.

The rings D are disposed on the lower side of the partition E and divide the space underneath the partition in two or more compartments communicating with each other through the space between the lower edges 55 of the ridges on the one side and the bowl F and the bottom G of the lower collecting vessel. As pointed out in the foregoing, the rings D have a double action, in that they will partly hamper an air current flowing 60 along the partition E, and partly separate liquid particles caught by such air current. On the comparatively sudden change in the direction of the air current the liquid particles continue in their movement, in the initial direction, owing to the inertia, and stick to the outer surfaces of the ring or the rings. While the drops are moving downwards through the combined influence of gravity and the action of the air current, 65 their volume is increased by absorption of further particles of liquid, which facilitates their passage through the openings between the lower edges of the rings and the bowl, 70 without the drops being again entrained by 75 the air. Fig. 1 of the drawing shows two concentric rings; it should be understood, however, that the invention is not limited to the said number of rings, as in certain vessels one ring may bring about the desired 80 effect, while in others a plurality of rings may be required. According to a further embodiment, ridges are used which are arranged tangentially, or nearly tangentially 85 and, broadly, in such a way, that they will 90 not permit air currents flowing underneath the partition to pass, without changes in the direction of movement, from an outer zone to an inner one, or vice versa.

Fig. 2 is a plan view of the embodiment 100 of ridges disclosed in Fig. 1, and Figs. 3 and 4 are plan views of embodiments in which the ridges are concentric to the bowl, but not annular. Fig. 5 shows an embodiment 105 wherein the ridges are disposed tangentially. The innermost circle in these horizontal pro-

jections indicates the outline of the upper part of the bowl. As set forth in the foregoing the ridges D are so arranged as to prevent, above all, particles of the heavier liquid from being entrained by the air currents to the lighter liquid. The ridges H, Fig. 1, disposed in an upper collecting vessel are, on the other hand, specially adapted to prevent particles of the lighter liquid from being entrained by the air currents to the heavier liquid.

These ridges H may also be made in different ways; for example, they may be shaped according to any of the embodiments shown in Figs. 2-5.

When using such ridges H, however, the outlet for the lighter liquid should be disposed as at J, Fig. 1.

What I claim as new and desire to secure

by Letters Patent of the United States is:— 20

In a centrifugal machine for separating liquids of different specific gravities, in combination, a bowl provided with openings for the passage of separated liquids, collecting vessels for the separated liquids disposed about said bowl, said vessels being separated by a partition, said machine being provided with a passageway affording communication between said vessels, a plurality of substantially tangential baffles extending from said partition and at an angle thereto and positioned adjacent said passageway so as to prevent the passage of particles of liquid entrained by air currents passing from one vessel to the other. 25 30 35

In testimony whereof I affix my signature.

K. P. NILSSON.
